MOLDED HANDLE TIE

Leon B. Cotton, Drexel Hill, Pa., assignor to I-T-E Circuit Breaker Company, Philadelphia, Pa., a corporation of Pennsylvania

Filed Oct. 31, 1960, Ser. No. 65,979

6 Claims. (Cl. 200—50)

This invention relates to circuit breakers of low current rating and more particularly to a novel molded handle tie whereby two adjacent circuit breakers may be manually operated and which permits the handle of a tripped circuit breaker to move to trip position while the handle of the other circuit breaker remains in the ON position.

Low current rated circuit breakers of the type customarily utilized in the home and for light industrial applications are often tied together for simultaneous manual operation. Circuit breakers of this type are manually operable between two extreme positions to open and close the circuit breaker. When the circuit breaker is tripped, there is biasing means which urges the operating handle to an intermediate position to indicate the tripped condition.

When a pair of circuit breakers protecting different branch circuits are tied together for simultaneous operation, if a fault should develop in one of the branches, it is most desirable that the branch having the fault be readily determinable. This can best be done by observing the positions of the circuit breaker operating handles.

If there is a rigid tie between the circuit breaker handles, should one of the breakers trip, its handle will remain in the ON position since the loading of the operating spring of the other circuit breaker cannot be overcome by the spring force of the tripped circuit breaker. Thus, it is necessary to provide a non-rigid type of connection between the operating handles of the circuit breakers in order that the handle of the tripped circuit breaker is free to move to trip indicating position while the handle of the other circuit breaker remains in the ON position.

The prior art has attempted to solve the above noted problem by providing overlapping handle extensions held by rivets, by providing a tie bar held by screws and brackets, by providing male and female handle extensions engaging each other with ample clearance, by providing a swiveling stepped cylindrical tie held in oversize holes in the handles, and by providing a cylindrical tie held by a loose bar disposed in handle apertures.

It is noted that each of these prior art devices consisted of many intricate parts and/or required a good deal of labor in order to mount the parts to the circuit breakers.

Accordingly, it is a primary object of this invention to provide a handle tie means which is of extremely simple construction and which is readily mounted to the circuit breakers. This is accomplished by providing a simple molded member which is disposed in the space between adjacent circuit breaker handles. The molded member is provided with an elongated slot which receives pins extending from the sides of the circuit breaker handles. The elongated slot provides a lost motion connection between the tie member and the circuit breaker handles, so that the handle of the tripped circuit breaker may move to trip indicating position without causing movement of the handle of the other circuit breaker from the ON position.

The possibility of binding between the handles and the molded member is substantially eliminated by providing a molded member with an extension. This extension is disposed within a groove formed by cooperating formations of the adjacent circuit breakers, which forms means for guiding the molded member in its sliding movement and also maintains the molded member spaced from the handles.

2

The pins in question are constructed of rolled sheet material. These pins are disposed within apertures in the handles and are force fitted therein.

Another object is to provide a handle tie means comprising a simple molded member.

Still another object is to provide a handle tie means which is secured to the circuit breaker handles by pins extending from these handles. These as well as other objects of this invention shall become readily apparent after reading the following description of the accompanying drawings in which:

FIGURE 1 is an end view of a pair of circuit breakers whose handles are tied together by a tie means constructed in accordance with the teachings of the instant invention.

FIGURE 2 is a fragmentary plan view of the circuit breakers of FIGURE 1 with the handles in the ON position.

FIGURE 3 is a view similar to FIGURE 2, with the handles of one circuit breaker in the ON position and the handle of the other circuit breaker in the trip position.

FIGURE 4 is a fragmentary side elevation of the circuit breakers of FIGURE 1 locking in the direction of arrows 4—4 of FIGURE 1.

FIGURE 5 is an exploded perspective of the handle tie and securing means therefor.

Now referring to the figures. Circuit breakers 10, 11 are shown mounted adjacent to one another in side by side relationship. The circuit breakers are of the type fully described in U.S. Patent 2,773,949. As is well known to the art, when circuit breakers of this type are mounted within a panel board, they are maintained substantially in the positions illustrated in FIGURE 1. Each of the circuit breakers 10, 11 is provided with a manually operating handle 12, which projects from the top of the circuit breaker housing. Handle 12 is pivotable from the ON position to the OFF position. When the circuit breaker has tripped, the operating mechanism thereof biases handle 12 to a trip position which is intermediate the ON and OFF positions.

Handle tie 13 is positioned between operating handles 12 of both circuit breakers 10 and 11, so that both circuit breakers are simultaneously operable to the OFF and ON positions, as will be more fully explained herein-after.

Handle tie 13 comprises a simple molded member having a narrow downward extension 14, which is disposed within groove 15 formed through the cooperation between raised housing portions 16 at the tops of adjacent circuit breakers 10, 11. Groove 15 serves as a means for guiding handle tie 13 in its sliding movement. Handle tie 13 is provided with an elongated slot 17 which receives pins 20—21, which extends toward each other from handles 12. Since pins 20, 21 are of identical construction, only pin 20 will be described. Pin 20 is constructed of rolled sheet material one end of which is upset to form transverse tabs 22.

Tie member 13 is mounted to circuit breakers 10, 11 by placing guide projection 14 into groove 15 and moving tie member 13 into alignment with handles 12. Pin 20 is then entered into handle aperture 23 of circuit breaker 11 from the left side thereof until tabs 22 prevent further movement of pin 20 to the right. At this time the right end of pin 20 is disposed within slot 17. It is to be noted that handle aperture 23 is slightly undersized with respect to pin 20, so that a forced fit is established to retain pin 20 mounted to handle 12. Pin 21 is similarly mounted to handle 12 of circuit breaker 10 by being entered into handle aperture 23 of circuit breaker 10 from the right side thereof.

It is readily seen that sliding movement of tie member 13 brings about the simultaneous operation of circuit

breakers 10, 11 to the ON and OFF positions. That is, to operate circuit breakers 10, 11 to the ON position, pins 20, 21 are picked up by end 31 of slot 17, and to operate circuit breakers 10, 11 to the OFF position, pins 20, 21 are picked up by end 32 of slot 17. As best seen in FIGURE 3, when one of the circuit breakers, in this case circuit breaker 10, is tripped, the handle 12 thereof is free to move to trip indicating position. In so doing, pin 21, in engagement with end 31 of slot 17, moves within tie member 13, so that pin 21 is at end 32 of slot 17. It is to be noted that the space between adjacent handles 12 is slightly greater than the width of tie member 13. Further, the cooperation of tie member extension 14 and guide slot 15 serves to maintain tie member 13 spaced from both handles 12. This insures that no binding action will take place between handles 12 and tie member 13, so that the handle of the tripped circuit breaker is free to move to trip indicating position.

Thus, this invention provides an inexpensive handle tie means, which permits the handle of the tripped circuit breaker to move to trip indicating position while the handle of the other circuit breaker remains in the ON position. The construction of the tie means is such that it may be conveniently mounted in operative position by a simple pin means extending from the handles of adjacent circuit breakers.

Although the invention herein has been described in connection with an exemplary embodiment, it is to be understood that variations and modifications may be made therein without departing from the spirit and scope 30 thereof, as defined in the following claims.

I claim:

1. A first and a second circuit breaker arranged in adjacent side by side relationship with their operating handles in alignment; each of said handles being manually movable between a first and a second position to operate said circuit breakers ON and OFF, respectively; each of said handles being movable to a third position intermediate said first and said second positions upon tripping of said circuit breakers; a handle tie positioned between said handles; means interconnecting said handle tie to said handles for simultaneous manual operation of both circuit breakers; said interconnecting means including individual unitary means mounted to each of said handles for loosely retaining said tie whereby the handle of one of said circuit breakers may move to its said third position while the handle of the other of said circuit breakers remains in its said first position; said tie being continuously disposed in a plane parallel to the planes defined by the movement of said circuit breaker handles; said handle tie comprising a slidably mounted block-like member having a projecting guide portion positioned within a slot defined by cooperating formations of said circuit breakers.

2. A first and a second circuit breaker arranged in adjacent side by side relationship with their operating handles in alignment; each of said handles being manually movable between a first and a second position to operate said circuit breakers ON and OFF, respectively; each of said handles being movable to a third position intermediate said first and said second positions upon tripping of said circuit breakers; a handle tie positioned between said handles; means interconnecting said handle tie to said handles for simultaneous manual operation of both circuit breakers; said interconnecting means including individual unitary means mounted to each of said handles for loosely retaining said tie whereby the handle of one of said circuit breakers may move to its said third position while the handle of the other of said circuit breakers remains in its said first position; said tie being continuously disposed in a plane parallel to the planes defined by the movement of said circuit breaker handles; said handle tie comprising a slidably mounted block-like member; having a projecting guide portion to be operatively engaged by a cooperating slot formation of said circuit breakers where-

5 by binding is prevented between relative movement of said handle tie and said circuit breaker handles; said individual means comprising a pin for each of said handles; said pins projecting from said handles to one another and being disposed within an elongated slot of said handle tie whereby said tie is retained in operative position; each of said pins comprising a tubular member force fitted within an opening of said handle.

3. A first and a second circuit breaker arranged in adjacent side by side relationship with their operating handles in alignment; each of said handles being manually movable between a first and a second position to operate said circuit breakers ON and OFF, respectively; each of said handles being movable to a third position intermediate said first and said second positions upon tripping of said circuit breakers; said first, second and third positions being arcuately disposed about a common pivot; a handle tie positioned between said handles; means interconnecting said handle tie to said handles for simultaneous manual operation of both circuit breakers; said interconnecting means including individual unitary means mounted to each of said handles for loosely retaining said tie whereby the handle of one of said circuit breakers may move to its said third position while the handle of the other of said circuit breakers remains in its said first position; said tie being continuously disposed in a plane parallel to the planes defined by the movement of said circuit breaker handles; said circuit breakers having portions cooperating to form means for guiding movement of said handle tie and maintaining the sides of said handle tie spaced from the handles of said circuit breakers whereby binding is prevented between relative movement of said handle tie and said circuit breaker handles.

4. An assembly means for interconnecting the handles 35 of a first and a second circuit breaker, each of said handles being movable manually to an ON position and an OFF position, each of said handles being movable automatically to a position intermediate said ON and OFF positions, said handles each being pivotally rotated in a first and a second plane respectively to said ON, OFF and intermediate positions; said circuit breakers being arranged in adjacent side by side parallel relationship so that said first and second planes are parallel, said interconnecting assembly means comprising a handle tie disposed between 40 said circuit breaker handles in a third plane parallel to said first and second planes, said tie including a positioning means engageable by cooperating means of said circuit breakers to maintain in the planar spacing between said tie and said circuit breaker handles, a first and a second unitary means to be attached to said first and second circuit breaker handles respectively, and including a portion projecting into cooperating means in said tie, said unitary means being the only members of said assembly means attached to said circuit breaker handles, said unitary means projecting portion engaging said cooperating 45 means of said tie to cause a movement of one of said circuit breaker handles to said ON or OFF position to be transmitted to the other of said circuit breaker handles, but permitting one of said circuit breaker handles to individually move to said intermediate position without effecting movement of the other of said circuit breaker handles, said tie being constantly contained within said third plane during said movements.

5. An assembly means for interconnecting the handles 65 of a first and a second circuit breaker, each of said handles being movable manually to an ON position and an OFF position, each of said handles being movable automatically to a position intermediate said ON and OFF positions; said handles each being pivotally rotated in a first and a second plane respectively to said ON, OFF and intermediate positions; said circuit breakers being arranged in adjacent side by side parallel relationship so that said first and second planes are parallel, said interconnecting assembly means comprising a handle tie disposed between said circuit breaker handles in a third 70 plane.

plane parallel to said first and second planes, said tie including positioning means engageable by cooperating means of said circuit breakers to maintain the planar spacing between said tie and said circuit breaker handles, a first and a second unitary pin to be attached to said first and second circuit breaker handles respectively, and including a portion projecting into cooperating means in said tie, said pins being the only members of said interconnecting assembly means attached to said circuit breaker handles, said pins projecting portion engaging said cooperating means of said tie to cause a movement of one of said circuit breaker handles to said ON or OFF position to be transmitted to the other of said circuit breaker handles, but permitting one of said circuit breaker handles to individually move to said intermediate position without effecting movement of the other of said circuit breaker handles, said tie being constantly contained within said third plane during said movements, said interconnecting assembly means being removable from said circuit breaker handles by the removal of said pins, the removing and attaching of said pins being readily accomplished while said circuit breakers are stationary in said first and second planes.

6. An assembly means for interconnecting the handles of a first and a second circuit breaker, each of said handles being movable manually to an ON position and an OFF position, each of said handles being movable automatically to a position intermediate said ON and OFF positions, said handles each being pivotally rotated in a first and a second plane respectively to said ON, OFF and intermediate positions, said circuit breakers being ar-

5 ranged in adjacent side by side parallel relationship so that said first and second planes are parallel, said interconnecting assembly means comprising a slidably mounted handle tie disposed between said circuit breaker handles in a third plane parallel to said first and second planes, said tie including a projecting positioning means engageable by cooperating slot means defined by housing formations of said circuit breakers to maintain the planar spacing between said tie and said circuit breaker handles, a first and a second unitary pin to be attached to said first and second circuit breaker handles respectively, and including a portion projecting into cooperating means in said tie, said pins being the only members of said interconnecting assembly means attached to said circuit breaker handles, said pins projecting portion engaging said cooperating means of said tie to cause a movement of one of said circuit breaker handles to said ON or OFF position to be transmitted to the other of said circuit breaker handles, but permitting one of said circuit breaker handles to individually move to said intermediate position without effecting movement of the other of said circuit breaker handles, said tie being constantly contained within said third plane during said movements.
